UNITED STATES PATENT OFFICE.

JEAN RÉOL, OF LYON, FRANCE.

PRESS FOR FORMING BRIQUETTES.

Application filed June 30, 1920. Serial No. 393,151.

(GRANTED UNDER THE PROVISIONS OF THE ACT OF MARCH 3, 1921, 41 STAT. L., 1313.)

To all whom it may concern:

Be it known that I, JEAN RÉOL, a citizen of the French Republic, and resident of Lyon, Rhone, France, have invented certain new and useful Improvements in Presses for Forming Briquettes (for which I have obtained patent in France December 8, 1914, and filed applications for patents in Great Britain April 20, 1914; Belgium, June 10 20, 1919; Italy, June 26, 1919, and in Spain, No. 70,378, dated November 29, 1919), of which the following is a specification.

This invention forming the object of the present application relates to a system of 15 pressing briquettes of coal or other agglomerable material by a simultaneous double compression and with varying intensity, with or without a binding material.

The invention will be fully described 20 with reference to the accompanying drawings.

Fig. 1 shows the arrangement in elevation following a longitudinal section through a vertical plane passing through the axis of 25 the machine.

Fig. 2 is a plan of the machine.

Fig. 3 is an end view showing the method of actuating the table.

Fig. 4 shows the valve casing of the 30 hydraulic cylinder.

This press consists essentially of a double base plate *a*, the two parts of which are symmetrical and designed to support all the parts of the machine.

35 A crank shaft *b* carries at each of its ends a gear wheel *c* receiving movement from pinions *d* fixed on the shaft *f* at the rear of the base plate, which receive motion from a motor or the like.

40 A connecting rod *g* actuated by the crank shaft *b* is articulated on a lever *h*, which is fulcrumed on a shaft *i* fixed on the two pedestals *j* rigidly mounted on the base plate *a*.

The upper pressing plunger *k* is articulated at *l* on the lever *h*; it is guided between two slides *m*, one of which (the left) is bolted on to the pedestals *j*, and the other (the right) forms part of a double pedestal *n* affixed to the pedestals *j* and supported by a ring *t* on the table of the press.

45 A crank shaft *o* articulated on the principal lever *h* passes through the centre of

table *p* carrying the moulds, and is pivotally connected to the lower lever *q*.

At the right end of the lever *h* is pivoted 55 an extractor *r*, working in guide pieces affixed to the pedestals *n*.

Below the lever *h* is arranged a table *p* provided with a number of sockets (in practice 10 to 12) rotating about a ring *t* and 60 supported by a circular piece *u* held in position by the extensions *v* fixed to the pedestals *j*, and by the small pillars *x* fixed to the double base *a*.

A surface bearing *y* is interposed between 65 the table *p* and its support *u*, which serves as a track for it to roll on and reduce the wear and tear of the machine. Below the table is arranged a lever *q* articulated on a stud *z* which is connected by means or links *w* to a hydraulic piston *A*, supported by a beam *B* forming an extension of the piston *A*, the said beam having a concave portion 70 to fit the convex part of the lever *q* to allow the rotation of the lever about its axis *z*.

On the lever *q* is fixed at *C* the lower pressure plunger *D* which is articulated and 75 fixed on the lever, in the same way the lever *q* is fixed and articulated on the piston of the press.

The left end of the lever *q* is terminated 80 by the shaft *E* engaging in a small wedge on the shaft *F* carrying a cage *G* which is engaged with the said wedge.

The shaft *F* which has a vertical movement works in two guide pieces *H* one fixed 85 to the base plate *a* and the other to the pedestal *j*. Two springs *I* supported on the lower guide piece *H* and held in tension, are traversed by the rod *F* which holds 90 them in position against the guide piece *H* by means of two regulating screws *J* screwed on the rod *F* to allow of regulation of the tension of the springs.

A casing *K* of a double valve with inlet *L* and an exhaust *M* is fixed on the hydraulic cylinder *N* and communicates with the latter by an orifice *O*; it carries an exhaust orifice *Q*.

95 To assure the convenient rotary movement of the table, a wall *R* bolted to the base plate *a* carrying a bracket *S* in which is mounted a vertical shaft *T*, carrying worm wheel *U* taking with it the worm *V*,

given motion by the wheel X which receives its motion from the wheel Z fixed on to the extension of the crank-shaft b and the pinion wheel W, fixed on the shaft of 5 the main pinion X or by any other suitable transmission, flexible or rigid.

A cam 1 is keyed on the vertical shaft T and communicates the movement to the 10 table by means of the groove 2 into which 15 successively enter and leave the cylindrical rollers 3, fixed on the shafts which are carried on the table.

The shaft T is held in its upper position in a bearing not shown in the drawings. 15 The said bearing is part of the casing of the distributor which may be of any suitable type, and of which the plates, not shown, serve to direct the material into the sockets of the table, and are fixed on the extension 20 of the shaft T.

After the description of the press and the examples of the drawings, it is easy to see how the apparatus works.

At the beginning of the movement (the 25 crank shaft being to the left and forming with the horizontal an angle of about 15°) the pressure plungers k and D, also the extractor block r are out the sockets of the table p.

30 One of the rollers 3 of the table is engaged in the acting part of the groove of the cam 1, and the table p driven by the cam and turns around the ring t.

The crank shaft continuing its movement 35 clockwise the pressure plungers enter the sockets of the table p. Just at this moment, one of the rollers 3 which by the calculated movement of the cam 1, has received an initial speed (v^1), arrives at a final speed 40 $y(v^1=0)$ in the nonoperating part of the cam, caused by a circular groove forming a continuation of the operating groove and is held, and consequently the table, in the position which it should occupy during the 45 working of the pressure plungers. The movement continues until the moment when the rod g is vertical also the crank shaft (maximum point of compression). The pressure plungers work in the socket as follows:—

The upper plunger k following the movement of the lever h descends into the socket, the lower plunger D worked by the lever q, which under the action of the crank o, 55 rotates about its axis z, rising in the socket.

In this movement of rotation of the lever q in consequence of the application of the lower part on the beam B of the hydraulic piston A, the axis z constitutes a fixed axis 60 of rotation (the incompressibility of the water in the cylinder N assuring the fixture of the said axis z, because the interior pressure applied to the outlet valve of the casing of the valve is calculated to be the same 65 as that imposed for the compressing of the

material). But at the same time the left end of the lever q by the intermediary of its axis E moves vertically on the rod F, and in consequence compresses the lower spring I and extends the upper spring I. 70

During this period of movement the extractor plunger r penetrates into the socket brought in front of it, and removes the compressed briquette and forces it below the table p where it falls on to a conveyor which takes it to any predetermined place. 75

The movement continues in the same direction after the passage of the vertical position of the crank corresponding to the vertical point of the crank shaft, the 80 lever h oscillates on its immovable axis i and its left part descends whilst the right is raised. The pressure plungers k and D also the extractor plunger, are removed from the socket leaving the table p free to 85 make a fresh rotation.

During this period one of the rollers 3 of the table disengages itself from the non-operating circular groove in the cam, which assures the stationary position of the frame, 90 and the operating groove engages the following roller to bring a new socket into line with the pressure plungers.

The movement is then continued in the way which has heretofore been described, 95 producing simultaneously the compression and the extraction of the briquettes.

It is to be noticed that the axis i of oscillation of the lever h is absolutely immovable because of the connection of the pedestals to the base a, the reaction acts on this axis at the moment of compression of the powdered material tending to lift this axis i, which tends also to drag away in an upward direction the pedestals j which in their turn tend to raise the base a (which is absolutely impossible). But if impossible whatever movement this base could have, this said movement (whatever it may be) would not be prejudicial to the working of the press because the table carrying the socket is supported on the pedestals j and the rigid pillars x fixed on the base a would sustain an angular movement, the force and symmetry would be the same, following a 100 common axis, and the whole would move or oscillate together. That which applies to the axis i of the head of the machine also applies to all the parts and would be displaced absolutely proportionally. The vertical shafts of the pressure plungers and extractors in every state would always fit exactly into the sockets, during the compression strokes.

Moreover, in the continuation of movement the lower spring I of the rod F actuated by the end of the lever q is detained and helped by this detention to the rotation of the lever q about its axis z by which a couple is formed by the tension of the said 105 110 115 120 125 130

spring and the pull of the crank *o*. This facilitates the oscillation of the lever *q*. Then after the complete detention of the lower spring *I*, the initial pressure of the 5 said spring is greater than the friction of the hydraulic piston *A* on the walls of its cylinder *N*, the axis *E* being the axis of oscillation of the lever *q* which enters with the piston *A* which then works as an ordinary air pump piston.

10 This phenomenon of aspiration which is of no practical value in the normal working, becomes of great use when the material is brought into the sockets foreign to those 15 constituting the product of agglomeration. In this case by reason of the additional pressure to that for which the exterior pressure of the exhaust valve *M* in the casing of the valve *K* has been calculated, the valve *M* 20 is raised allowing the water in the hydraulic cylinder to escape and the lower pressure plunger *D* descends instead of rising, at the same time as the hydraulic piston *A* to which it is fixed. Under these conditions at the 25 moment when the general movement carries the fulcrum of the lever *q* from *z* to *E*, the hydraulic piston *A* working in aspiration, provides, at the time of this aspiration the

opening of the valve *L* of the casing of the valve *K*, and by this method refills the 30 cylinder *N* replacing also the water which the piston *A* has accidentally evacuated, and which without the apparatus described would be detrimental to the ordinary rigid press driven by the ordinary mechanical 35 means and devoid of flexibility.

What I claim is:—

A double compression press comprising a fixed support, a rotary mould table, an operating lever pivoted on said support, a compression plunger pivotally connected to the operating lever, an ejector plunger also pivotally connected to said lever, a second compression plunger arranged to move in the opposite direction to the first, a rod and lever connecting the second compression plunger to the operating lever, a hydraulic cylinder, a piston therein, a block carried by said piston, the said connecting lever being arranged on said block, and a rotary cam 45 arranged to impart maximum speed to the table during the periods between compression and to hold the table against movement during the periods of compression.

In witness whereof I affix my signature.
JEAN RÉOL.
